UNITED STATES PATENT OFFICE.

WILLIAM E. ARNOLD AND HOBART G. ARNOLD, OF ROCHESTER, NEW YORK.

IMPROVED SASH AND BLIND FASTENER.

Specification forming part of Letters Patent No. 33,423, dated October 8, 1861.

To all whom it may concern:

Be it known that we, WILLIAM E. ARNOLD and HOBART G. ARNOLD, of Rochester, in the county of Monroe and State of New York, have invented certain new and useful Improvements in a Combined Fastener and Lock for Sash and Blinds, of which the following is a full and exact description, reference being had to the accompanying drawings, making part of the specification, and to the letters of reference marked thereon, the same letters referring to like parts in all the drawings.

In the drawings, Figure 1 is a perspective view of the lock. Fig. 2 is an inside or back view of the box, showing a plan of it. Fig. 3 is the same with bolt B and slide C arranged for left hand. The shortest cog or cam on the slide connects with the bolt, so as to hold it from being easily moved inward and upward. Fig. 4: Here the longest cog or cam on the slide C connects with the bolt B, so as to allow a free movement of the bolt inwardly from a pressure on the outer end. Here also the slide C extends below the box for purposes hereinafter described. Figs. 5 and 6 are the same as Figs. 3 and 4 reversed. Fig. 7: Here the sliding back partly covers the box, bolt B, and slide C, and in connection with Fig. 8 is intended to show the principle of locking and unlocking the fastener. Figs. 9 and 10 are the same as Figs. 7 and 8 reversed. Figs. 11 and 11 and 12 and 12 show the bolt B and slide C in plan and cross-sections. Figs. 13, 14, 15, 16, and 17 show plans of the sliding back with corresponding numbers of keys belonging to them.

The nature of our invention consists in so constructing and arranging a sliding back to a box with a bolt or slide, or both, as to form a combined fastener and lock without necessarily complicating the forms by the latter, while the latter requires only the particular key belonging to it to form a convenient, safe, and reliable lock, the security being increased by the great variety of keys, their perfect adaptation, and the peculiar construction of the openings or forms in the sliding backs, which are made to receive them; also, in constructing and arranging an adjustable slide with a cog or cam on each edge, one longer than the other, so as at pleasure to have it hold the bolt B firmly when down or let it be

easily pressed inward and upward. To do this we construct a box, as shown in Figs. 1 and 2, a bolt, as shown in Figs. 11 and 11, a slide, as shown in Figs. 12 and 12, and put them together, as shown in Figs. 3 and 4. It will be seen that the slides C in these two drawings are reversed. The shortest cog or cam D in Fig. 3 connects with the bolt, the lower edge being a little below the opening in the bolt, and holds the latter from being pushed inward by any pressure upon the outer end of it, which is in many instances of great importance; but when the slide is raised a little by the nib which is shown in Fig. 1, letter F, the cog D enters the opening in the bolt B, and from that point upward the bolt is perfectly free, except the weight of the slide, and is easily pressed inward. This arrangement is in most cases particularly desirable for sash which rise and lower. In Fig. 4 the slide is reversed, and the longest cog or cam E connects with the bolt B, but does not leave the opening when fully down. Consequently a slight pressure on the end of the bolt B will move it inward. The arrangement last described is sometimes very important when used for blinds or swinging sash, and there are some instances when it is needed for sash which rise and lower.

Having described the working parts of the fastener, we will now add the back, and here, instead of a stationary one, we will insert a sliding back, as shown in Fig. 7, letter L. The sliding back is here moved forward to the front edge of the box, and the small nibs in the back of the slide C and bolt B are in the straight grooves M and N. Consequently the slide and bolt may be worked as freely as they could with only a common or stationary back.

In Fig. 8 the sliding back is moved backward to the back edge of the box, bringing the small nibs on the slide C and bolt B into the lower notches of the sliding back, by which they are held firmly, and any effort to move the bolt or slide will be ineffectual so long as the sliding back remains in the position here shown.

In Fig. 7 we have the fastener brought to a high state of perfection for all ordinary purposes without any complication. In Fig. 8 we have the same fastener firmly locked without any addition. But to make the lock con-

venient and desirable for all necessary purposes we have constructed not only one but a large number of keys, all of which are made upon the principle shown in Figs. 13, 14, 15, 16, and 17, each form varying a little in size from those here shown. To each of these keys we have fitted a sink or sinks in each of the corresponding numbers of the sliding backs. These sinks are made partly in the form of dovetails and are open in front or in the direction the key needs to bear in unlocking the fastener. Consequently each key needs to fit perfectly. If a little too large, it will not enter. If too small, it may lock the fastener, but not unlock it, as it will find nothing in that direction to bear against.

By referring to letters O and O, Figs. 13 and 13, the form of the sink in that number of the sliding back with the form of the key belonging to it will be perfectly understood, and so in each of the corresponding letters and numbers.

In Fig. 14 the key fits to each side of the center dovetail.

The form of each key in Figs. 15, 16, and 17 is such as to require (in some instances) two or more sinks in each corresponding number of the sliding back, as there shown. The key-sinks, grooves, and notches in the sliding backs may appear in the drawings as though they were cut entirely through; but we cast a web over them, in order to give sufficient strength.

In fitting the sliding backs to the box we let the front end (letter T) down a little below the edge of the box; but we leave the back end (letter U) a little above, so that when the front edge of the box is screwed down as hard as it should be the back part will bear on the back part of the sliding back sufficiently to hold it in its proper place. Thus by turning the screws the sliding back may be tightened or loosened, as desired. The tighter they are of course the more difficult to pick them. By raising the ribs F on the slide C, as shown in Fig. 1, as far as it will go the bolt B is drawn in even with the box. The motion downward is by their own weight.

Letter W in Fig. 1 shows the key-hole through which the keys pass to the sinks in the sliding backs. To lock or unlock the fastener, first be sure that the key is in the place designed for it. Then press sufficiently by the hand to keep it there, and bear with the same hand in the opposite direction from which you wish the sliding back to go—if to lock the fastener, bear the hand toward the

front edge of the lock; if to unlock it, bear in the opposite direction.

For blinds or swinging sash some expense may be saved by connecting the lower end of the slide C with a catch for that purpose and dispense with the bolt B; but here, however, an objection may sometimes arise, owing to the sagging of the blinds or sash; but by connecting the catch with the bolt B this objection is entirely obviated. The bolt B should in this case connect with the longest cog or cam on the slide C, so as to allow it to work freely by a pressure on the end, thus allowing it to pass freely over the catch prepared for it. Here also a cheap form of the fastener may be made by dispensing with the slide C, letting one or both of the nibs which are shown in Fig. 11 pass through the box for working the bolt. This description answers equally well for all sash as well as blinds; but this modification of the fastener is less perfect, and will not work as well as the bolt and slide together.

It will be seen that the lock as shown in the drawings is designed to be screwed to the surface of the blinds, sash, or moldings. When desired, it may be let in even. In such case the slide C should work within the box, as shown in Figs. 8, 9, and 10.

When the slide and bolt are both used in the fastener, a locking-nib or its equivalent may be used on only the bolt or slide, if desired. In Figs. 9 and 10 a nib is on only the slide C; but in Figs. 7 and 8 they are on both the slide C and bolt B. It will be observed that either one will lock them both securely either up or down and for either hand.

Having thus fully described our invention and its utility, what we claim as new, and desire to secure by Letters Patent, is—

1. The constructing and arranging of the sliding back or backs L, in combination with the box A and key or keys for the purpose of locking the bolt B or slide C or their equivalents either down or up, substantially as herein set forth and described.

2. The adjustable slide C, when combined and arranged with the box A and bolt B, so as at pleasure to hold the bolt B firmly when down or let it be easily pushed inward and upward by a pressure on the outer end, substantially as herein described.
